UNITED STATES PATENT OFFICE.

NILS H. ANDERSON, OF MIDDLETOWN, CONNECTICUT, ASSIGNOR TO THE NOISELESS TYPEWRITER COMPANY, OF MIDDLETOWN, CONNECTICUT, A CORPORATION OF CONNECTICUT.

TYPE-WRITING MACHINE.

1,261,752.

Specification of Letters Patent.

Patented Apr. 9, 1918.

Application filed August 6, 1918. Serial No. 783,831.

To all whom it may concern:

Be it known that I, NILS H. ANDERSON, a citizen of the United States, residing at Middletown, in the county of Middlesex and 5 State of Connecticut, have invented certain new and useful Improvements in Type-Writing Machines, of which the following is a full, clear, and exact description, such as will enable others skilled in the art to 10 which it appertains to make and use the same.

This invention relates to typewriting machines, and with regard to certain more dominant features thereof, to type actions 15 and associated and co-acting parts thereof.

One of the objects of the present invention is to provide a type action of simple and practical construction which will be durable and efficient in action. Another object is to provide a type action of the above 20 character having a desirable touch and capable of being operated at high speed. Another object is to provide a type action of the above first mentioned character which 25 will be comparatively noiseless in operation. A further object is to provide practical means for mounting and connecting the various parts so as to enhance their ease of movement and reduce wear. Other objects will be in part obvious and in part 30 pointed out hereinafter.

The invention accordingly consists in the features of construction, combinations of elements and arrangement of parts which 35 will be exemplified in the construction hereinafter set forth, and the scope of the application of which will be indicated in the following claims.

In the accompanying drawings wherein is 40 shown one of the various possible embodiments of this invention,

Figure 1, 2 and 3 are elevational views of a type action and co-acting parts sufficient in detail to understand the application of 45 the present invention, in normal, intermediate, and printing positions, respectively;

Fig. 4 is a plan view showing a plurality of type actions in their radially disposed relation to the printing point;

50 Figs. 5, 6 and 7 are detail views showing the manner of connecting the type bar to the actuating mechanism.

Fig. 8 is a detail perspective view of a pivot member, and

Fig. 9 is a detail perspective view of a 55 part of the type action.

Similar reference characters refer to similar parts throughout the several views of the drawings.

Referring now in detail to the accompanying drawings, and more particularly to Fig. 1, a cylindrical platen roller 1, here shown diagrammatically in section, is provided with a flat metallic platen 2. The platen roller is mounted in any suitable 60 form of vertically shiftable carriage, not herein shown, movable in the well-known manner from right to left, under the action of an escapement mechanism 3 operated at each actuation of the machine. Each key-lever 4 is connected with a type carrier 5 mounted to slide back and forth relatively to the platen by means of suitable pressure multiplying and speed controlling elements 65 as will now be described in detail.

The type carrier is provided at its rear end with three type 6 for printing different case characters when co-acting with the flat platen 2 as the carrier slides rearwardly between a base-plate 7 and a top plate 8 in 70 the upper rear part of the machine. The carrier is held and guided in its movement by upwardly and downwardly projecting pins 10 and 11, mounted in the bottom and 75 top plates respectively. To the central part 80 and at either side of the type carrier is connected a pair of substantially flat sheet metal links 12 of more or less resilient material which are adapted to be snapped over a central pivot member 13, as clearly 85 shown in Fig. 8. The pivotal connection between the type action and the type carrier comprises what might be termed a ball and socket connection, that is, the type carrier is provided with a central opening having 90 a single flattened side within which is placed the spherical pivotal member 13, having a notch 9 cut in one side to engage the flattened side of the opening in the type carrier, thus to prevent lateral removal 95 thereof when assembled. The pivotal member is also provided with a stud at each side thereof adapted to engage openings in the 100 ends of the duplex links 12 which are

105

sprung into position thereover in the manner shown in Figs. 5 and 6. This form of connection permits a slight amount of angular movement between the parts of the type 5 action and more specifically between the connecting links 12 and the type carrier itself, as well as providing a more simple form of connection permitting greater ease and a less expense in assembling and changing 10 parts.

The links 12 are connected at their central portion by means of a stud 14 to prevent spreading and are also provided with a pivotal connection at their opposite ends with 15 a pair of links 15, the opposite ends of which are in turn pivotally mounted upon an L-shaped bracket 16 mounted on a front plate 17 of the frame of the machine.

This bracket is capable of adjustment in 20 a fore and aft direction by means of a set-screw 18 engaging a tapped-out recess in the front wall and is held in adjustment by means of a vertically disposed clamp screw 20 engaging a similarly tapped-out recess 25 intermediate adjacent actions, as clearly shown in Fig. 4. By loosening the clamp-screw 20 between any two adjacent actions, the adjusting screw 18 of either action may be turned in one direction or the other to 30 vary the limit of throw of the type carrier, thus regulating the pressure with which the type co-acts with the paper carried by the platen. As the links connecting the bracket and the type carrier form a toggle which 35 assumes extended position, as shown in Fig. 3, when the type action is actuated, the limit of throw of any type carrier can thus be positively adjusted and the pressure of all the type actions made uniform, thus producing 40 a typewritten page which will be conspicuous for its absence of extremely heavy or light printed characters.

The link 15 is composed of two parts, one upon each side of the bracket, and each 45 part is provided with an off-set portion 21 to which is pivotally connected the rearward arm 22 of a momentum acquiring means, preferably a momentum accumulator weight 23, which arm in turn, is pivotally connected near its middle to the upper arm 24 of a sub-lever, preferably a bell-crank lever. This bell-crank lever is 50 composed of two parts mounted on either side of the bracket 16 and pivoted at 25 on 55 the lower part thereof as shown clearly in Fig. 9.

This bell-crank lever is provided with two arms 26 and 27 extending forward and rearward, respectively, from the pivot 25. 60 The forward arm 26 is adapted to co-act with a pad 29 of felt or other suitable semi-resilient material mounted upon a support 28 in the front wall 17 of the machine when the type action is moved to printing position. The rear arm 27, which is the longer 65

of the two, is provided with an upper convex surface and is adapted to coact with a second sub-lever 30 pivotally mounted at its rear end 31 on a transverse wire 32 having a relatively fixed position in the frame of 70 the machine.

It will, of course, be understood that the wire 32, upon which the sub-lever 30 is mounted, is common to all of the type actions. As herein shown, wire 32, upon 75 which the open forked end 31 of the lever 30 is mounted, is reduced or flattened on one side. This form of construction facilitates the assembling or removal of the lever, for it will be clear from the drawings that by 80 swinging the lever 30 downwardly into a vertical position, after removing the action and disconnecting the pull wire, the reduced or flattened portion of the wire 32 will then occupy a relative position parallel 85 to one of the straight sides of the open end, thus permitting the lever 30 to drop away therefrom.

Near the forward end of the lever 30 is pivotally connected a pull wire 33 provided 90 with a suitable adjustable connecting means or clip 34, the lower end of which is connected with the body portion of the key-lever 4.

It will thus be seen that as the key-lever 95 4 is depressed, or moved on its printing actuation stroke, the lever 30 and rear arm 27 of the bell crank sub-lever will have a rocking or heel and toe action, the points of contact, or power transmitting portions, 100 of the sub-levers progressively approaching the fulcrum of the bell crank lever. Such form of connection has several material advantages; for instance the point of initial engagement between these parts 105 when the action is in normal position provides a relatively large leverage for the bell crank lever, which moves the type carrier toward the printing position, thus producing an easy and desirable initial touch. 110 However, as the key-lever continues its downward movement under the touch of the operator, the point of contact between the lever 30 and the bell crank lever arm 27 moves toward the pivot point 25, thus reducing 115 the leverage on the bell crank lever, but increasing its rate of movement, thereby materially increasing the manifolding properties of the action as a whole.

In order to further increase the pleasantness of touch in an action of this character, the key-lever is composed of two parts, one of which 35 is of relatively heavy material and is pivotally mounted at its rear end to a fulcrum bar 36. The other 4 is of relatively 125 light material and is riveted or otherwise secured at 37 to the under side of the main portion 35 of the key-lever. The downward movement of the key-lever is limited by a pad 38 of felt or other semi-resilient 130

material positioned to receive and arrest the forward end 40 of the member 35. The upward movement of the key-lever is limited by a similar pad 41 mounted at the top 5 of a comb member 42 adapted to guide the key-lever 4 in its up and down movement. It will thus be seen that as the key-lever 4 is depressed, the body portion 35 co-acts with the stop 38 and its movement is arrest- 10 ed. The key itself, however, being mounted upon the part 4 of relatively lighter material presents a certain resiliency to the finger of the operator which renders the rapidly repeated operations less tiresome.

15 A return spring 43 is adjustably connected to a downwardly projecting lug 44 on the under side of the key-lever. The other key-levers (not shown) are provided with similar springs, all of which are connected 20 to a single yoke 45 which in turn is connected by means of a link 46 to a fixed portion 47 of the front part of the frame. By turning a holding nut 48 on the forward end of the connecting link 46 the tension of all 25 the key-levers may be simultaneously regulated.

30 As these several features regarding the key-lever construction and adjustment form no part of the present invention specifically, except in so far as certain features co-act with the type action as a whole, it is thought to be unnecessary to describe the same more in detail, as they will form the subject-matter of one or more separate applications.

35 Instead of positioning the universal bar beneath the key-levers, as in many forms of front-strike machines, it is in this embodiment positioned in the upper front part of the machine whereby it may be actuated di- 40 rectly by similar elements in each type action. As herein shown, the universal bar comprises a frame 50 in the form of an arc and is positioned just below and in rear of the pivot point 25 of each bell crank lever.

45 A fork or yoke 51 is swiveled on the rear- 50 wardly extending arm 27 near the point of connection of a return spring 52 of each bell crank lever and normally rests slightly above but straddling the universal bar. The uni- 55 versal bar is pivotally supported by means of a plurality of arms 53 of substantially the same length connected to depending brackets 54 from the frame of the machine. The lower part of the universal bar frame is piv- 60 otally supported at the ends of three arms 55 of substantially the same length, only one of which is herein shown, connected respectively with either end and the center of a universal rock shaft 56. The rock shaft is 65 provided with a downwardly extending arm 57 connected at its lower end with an adjustable pull wire 58 extending fore and aft of the machine; the rear end of the pull wire being connected with the rocker member of the escapement mechanism 3. The pull wire

58 passes freely through an opening 60 in the transverse beam 47 of the frame of the machine as well as the comb 42 for the key- 70 levers. A self-locking adjusting nut 61 is provided at the forward end of the pull wire for adjusting the distance between the fork and universal bar, and another 62 at a point in the rear of the beam, between which second nut 62 and beam 47 is coiled a spiral return spring 63. By means of these ad- 75 justing means the relation of the universal bar 56 to the bell crank lever may be regulated as well as the proper timing of the escapement mechanism and tension of the action as a whole. However, as these fea- 80 tures form no part of the present invention specifically, except in so far as they co-act with the type action, a more detailed description of the various features and ad- 85 vantages is believed to be unnecessary.

The operation of the present device is sub- 85 stantially as follows:

Assuming a machine to be in normal position, as shown in Fig. 1, as the key-lever 4 is depressed, or printingly actuated, move- 90 ment is transmitted to the pull wire 33 connected with the body portion 35 of the key- 95 lever to the forward end of the lever 30 which in turn rocks downwardly upon the upper curved surface of the rear arm 27 of the bell crank-lever. This movement causes the upper end of the bell crank arm 24 to swing rearward on its printing movement about its pivotal point of support 25, which in turn carries the rear arm 22 of the mo- 100 mentum accumulator rearward and down- 105 ward. As the movement continues, the toggle formed by the links 15 and 12 moves toward straightened position, as shown in Fig. 2. Likewise the rear arm 22 of the 110 momentum accumulator and the upper or longer arm 24 of the bell crank lever assume a partially extended reverse toggle. As soon as the parts reach the position shown in Fig. 2, the downward movement of the body por- 115 tion 35 of the key-lever is arrested by the semi-resilient pad 38 engaging the forward end thereof, which of course, arrests the key- 120 lever proper in a silent and resilient manner. As this action takes place so rapidly under the normal staccato touch, the weighted end 23 of the momentum accumulator or energy-storing means acquires a certain amount of momentum or force, depending partially on the length of its swinging 125 radius, in rearward and downward direction to complete the printing operation by forcing the type carrier to the printing plane, as shown in Fig. 3, that is, with the type in contact with the paper carried by the platen. 130 It will be noted that at this point the toggles formed by the links 12 and 15 as well as the reverse toggle formed by the rearwardly ex- 135 tending arm 22 of the momentum accumu- lator and the upwardly extending arm 24 of

the bell crank lever assume a straightened positions. It will also be noted that in the position shown in Fig. 3, the power transmitting portion of the rear arm 27 of the bell crank lever has moved out of contact with the power transmitting portion of the lever 30 and has placed the spiral return spring 52 under tension; there is therefore nothing to prevent the momentum accumulator from performing its natural tendency to rebound from stop bar 29 with the assistance of this return spring, to carry the type immediately out of engagement with the platen regardless of the release of the key-lever. It is during the final movement, that is, while the carrier is moving from the position shown in Fig. 2 to that shown in Fig. 3, or while movement of the type carrier is effected by the energy stored in weight 23, that the fork 51 carried by the rear arm 27 of the bell crank lever coacts with the universal bar 50 to urge the same downward. This downward movement of the universal bar will, through its connecting mechanism, rotate the universal rock shaft 56, which in turn, through the pull wire 58, actuates the dog rocker of the escapement mechanism 3. Owing to its mounting the universal bar will have a slight movement longitudinal of the sub-lever, or arm 27, and the element 51, being movably connected to said sub-lever will readily follow this longitudinal movement and be retained in pressing position, thus dispensing with substantial friction between the universal bar and this sub-lever during actuation of the escapement.

The escapement mechanism which is preferably of the "reverse" style, that is, with the fixed dog normally in engagement with the teeth, will complete its operation on the down stroke of the key lever when normally operated, thus permitting the carriage to move a letter space distance from the right to left. The movement of the type from the position shown in Fig. 2 to that shown in Fig. 3, and return, is almost instantaneous and yet being pressure-operated by means of toggles and power multiplying devices interposed between the type carrier and the key lever, its operation is substantially noiseless.

When the key-lever is released the parts naturally return to the position shown in Fig. 1, under the action of the several return springs 43, 52 and 63 which all co-act one with the other to produce the desired result.

A pad 64 is provided on the upper surface of the front wall of the machine having an upwardly and rearwardly inclined upper surface co-acting with an inclined surface of the under side of the momentum accumulator weight 23 adapted to cushion its return and prevent a rebound thereof. The center of the weight 23 does not move in the

arc of a circle, due to its compound pivotal connections and the path of travel of the final portion of its return movement is in a substantially straight line at a very slight angle to the upper surface of this pad. Referring to Fig. 1, it will be seen that the weight 23, will be translated initially toward the printing plane as soon as the arm 24 is actuated on its printing stroke, said weight being so disposed relative to the pivotal connecting point 15 as to initially translate in a rearward direction. The angle between the link 22 and the arm 24 is an obtuse angle, so that the type assumes position closer to the platen at the time the weight is in its most effective forcing position than it would be if said angle were acute initially.

It will be noted that the various parts comprising the present embodiment of the invention are so constructed and connected as to cause a minimum amount of wear; the various cushioning and spring devices for arresting the movement of such movable parts produce, in their co-action with the other parts, a machine which is substantially silent in its operation.

It is thus seen that this invention provides a practical and simple construction which is durable and highly efficient in action and one that is adapted to accomplish, among others, all of the objects and advantages above set forth.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

Having described my invention, what I claim as new and desire to secure by Letters Patent is:

1. In a typewriting machine, in combination, a platen, a type carrier adapted to coact therewith, a key lever and intermediate mechanism for actuating said type carrier, said mechanism including two levers with a shifting point of contact, a universal bar in the path of travel of one of said levers, and means adapted to effect printing and carry said levers out of contact one with the other whereby the universal bar is actuated.

2. In a typewriting machine, in combination, a platen, a type carrier adapted to coact therewith, a key lever for actuating said type carrier, and intermediate mechanism between said lever and said type carrier comprising a toggle, a bell crank lever connected therewith having a rearwardly extending arm and a lever adapted to have a rocking engagement therewith as the key lever is depressed.

3. In a typewriting machine, in combination, a platen, a type carrier adapted to coact therewith, a key lever for actuating said type carrier, intermediate mechanism between said lever and said type carrier comprising two members having a rocking engagement with each other as the key lever is depressed, and means adapted to carry said members out of engagement with each other

5 10 15 20 25 30 35 40 45 50 55 60 65 70 75 80 85 90 95 100 105 110 115 120 125 130

7. In a typewriting machine, in combination, a platen, a type carrier adapted to coact therewith, a key lever for actuating said type carrier, intermediate mechanism between said lever and said type carrier comprising two members having a rocking engagement with each other as the key lever is depressed, and means adapted to carry said members out of engagement with each other during the printing operation.

4. In a typewriting machine, in combination, a platen, a type carrier adapted to coact therewith, a key lever for actuating said type carrier, intermediate mechanism between said key lever and said type carrier comprising two members having a rocking engagement with each other as the key lever is depressed, and means adapted to carry said members out of engagement with each other

10 15 20 25 30 35 40 45 50 55 60 65 70 75 80 85 90 95 100 105 110 115 120 125 130

7. In a typewriting machine, in combination, a platen, a type carrier adapted to coact therewith, a key lever for actuating said type carrier, intermediate mechanism between said key lever and said type carrier comprising two members having a rocking engagement with each other as the key lever is depressed, and means adapted to carry said members out of engagement with each other during the printing moment.

5. In a typewriting machine, in combination, a platen, a type carrier adapted to coact therewith, finger-actuated means for operating said type carrier, and intermediate mechanism between said type carrier and said finger actuated means for transmitting motion from one to the other, said intermediate mechanism comprising a bell crank lever, a member adapted to have a rocking engagement therewith as the finger-actuating means is depressed, and a plurality of toggles interposed between said bell crank lever and said type carrier adapted to assume extended position at the printing moment.

6. In a typewriting machine, in combination, a platen, a type carrier adapted to coact therewith, finger-actuated means for operating said type carrier, and intermediate mechanism between said type carrier and said finger actuated means adapted to transmit motion from one to the other, said intermediate mechanism comprising a lever, a member adapted to have a rocking engagement therewith as the finger-actuating means is depressed, a plurality of toggles interposed between said lever and said type carrier adapted to assume straightened position during the printing moment, and means for returning the said parts to normal position.

7. In a typewriting machine, in combination, a platen, a type carrier adapted to coact therewith, finger-actuated means for operating said type carrier, and intermediate mechanism between said type carrier and said finger-actuated means adapted to transmit motion from one to the other, said intermediate mechanism comprising a bell crank lever, a member adapted to have a rocking engagement therewith as the finger-actuated means is depressed, a plurality of toggles interposed between the pivot point of said bell

crank lever and said type carrier adapted to assume straightened position during the printing moment, and means adapted to withdraw the type carrier from its printing position independently of the release of the finger-actuated means.

8. In a typewriting machine, in combination, a type carrier, a key lever having a body portion and an actuating portion of different degrees of resiliency, intermediate connections between the body portion of said key lever and said type carrier, and a resilient stop adapted to engage the body portion of said key lever for arresting its downward movement prior to the printing moment.

9. In a typewriting machine, in combination, a type carrier, a key lever having a body portion and an actuating portion of different degrees of resiliency, connections between the body portion of said key lever and said type carrier adapted to gradually increase and then decrease the rate of movement of the carrier, and a resilient stop adapted to engage the actuating portion of said key lever adapted to arrest its return to normal position.

10. In a typewriting machine, in combination, a type carrier, a key lever having a body portion and an actuating portion of different degrees of resiliency, a toggle between the body portion of said key lever and said type carrier, and separate stops adapted to engage the body portion and the actuating portion of said key lever on its downward and upward movement, respectively.

11. In a typewriting machine, in combination, a type carrier, a key lever, intermediate mechanism therebetween comprising a bell crank lever, an actuating member having rocking engagement with one arm of said bell crank lever, and a resilient stop adapted to co-act with another arm for silently arresting its movement as the key lever is depressed.

12. In a typewriting machine, in combination, a type carrier, a key lever, intermediate mechanism therebetween comprising a bell crank lever, an actuating member having rocking engagement with one arm of said bell crank lever, a resilient stop adapted to co-act with another arm for silently arresting its movement as the key lever is depressed, a universal bar positioned in the path of travel of one of said arms as it oscillates, and means for adjusting its position toward and from the normal position of said arm.

13. In a typewriting machine, in combination, a type carrier, a key lever, a bell crank lever interposed therebetween operatively connected with both, a universal bar in the path of travel of one of the arms of said bell crank lever adapted to be actuated thereby, and a swiveled contact member carried by said bell crank lever for directly actuating said universal bar.

- 6
14. In a typewriting machine, in combination, a type carrier, a key lever, a bell crank lever interposed therebetween and connected with both, a universal bar in the path of travel of one of the arms of said bell crank lever adapted to be actuated thereby, and a swiveled fork carried by one arm of said bell crank lever normally resting above said universal bar.
15. In a typewriting machine, in combination, a type carrier, a key lever, a lever interposed therebetween and connected with both, a universal bar in the path of travel of one of the arms of said lever adapted to be actuated thereby, and a fork carried by one of said arms of said lever engaging both sides and top of said universal bar during the printing moment.
16. In a typewriting machine, in combination, a key lever, a type carrier, means for moving the type from the key lever at a gradually increasing, thence at a gradually decreasing rate, and means for relieving the key from work during the final travel of the type carrier, said means comprising two co-acting members, and means adapted to carry said members out of engagement after the movement of the key lever has been arrested and to urge the type into engagement with the paper.
17. In a typewriting machine, in combination, a platen, an escapement mechanism for controlling the letter spacing thereof, a type carrier adapted to coact with the paper carried by said platen, a key lever for actuating said type carrier, means for moving the type from the key-lever at a gradually increasing and thence at a gradually decreasing rate, a universal bar directly associated with said means, and means for actuating said universal bar in effecting printing after the movement of the key lever has been arrested.
18. In a typewriting machine, in combination, a platen, escapement mechanism for controlling its letter spacing movement, a type carrier adapted to coact with said platen, a key lever, means for moving the type carrier from the key lever at a gradually increasing and thence at a gradually decreasing rate, means for arresting the key lever prior to the printing moment, and means for relieving the key from further work during the final travel of the type and for actuating the escapement mechanism independently of the subsequent movement of the key lever.
19. In a typewriting machine, in combination, a type carrier, a key-lever, devices whereby on printing actuation of said key-lever said type carrier is moved to the printing plane including a toggle the links of which are operatively connected with said parts and lie at an obtuse angle when said toggle is at the beginning of its printing stroke, and a weight connected to one of said links.
20. In a typewriting machine, in combination, a type carrier, a key-lever, devices whereby on printing actuation of said key-lever said type carrier is moved to the printing plane including a toggle the links of which are operatively connected with said parts and lie at an obtuse angle when said toggle is at the beginning of its printing stroke, and a weight pivotally connected to one of said links as to initially move toward the printing plane.
21. In a typewriting machine, in combination, a type carrier, a key-lever, and devices including a momentum acquiring means whereby on printing actuation of said key-lever, said type carrier is moved to the printing plane, and thereafter assumes a position away from the printing plane when the key-lever is at the limit of its printing stroke, comprising a sub-lever to which said momentum acquiring means is connected and a sub-lever connected to said key-lever, said sub-levers coöperating to transmit varying force on printing actuation of said key-lever.
22. In a typewriting machine, in combination, a type carrier, a key-lever, and devices including a momentum acquiring means whereby on printing actuation of said key-lever, said type carrier is moved to the printing plane, and thereafter assumes a position away from the printing plane when the key-lever is at the limit of its printing stroke, comprising a sub-lever to which said momentum acquiring means is connected and a sub-lever connected to said key-lever, said sub-levers coöperating to transmit decreasing force on printing actuation of said key-lever.
23. In a typewriting machine, in combination, a type carrier, a key-lever, and devices including a momentum acquiring means whereby on printing actuation of said key-lever, said type carrier is moved to the printing plane, and thereafter assumes a position away from the printing plane when the key-lever is at the limit of its printing stroke, comprising a sub-lever to which said momentum acquiring means is connected and a sub-lever connected to said key-lever, said sub-levers coöperating to transmit increasing rate of movement to the first mentioned sub-lever on printing actuation of said key-lever.
24. In a typewriting machine, in combination, a type carrier, a key-lever, and devices including a momentum acquiring means whereby on printing actuation of said key-lever, said type carrier is moved to the printing plane, and thereafter assumes a position away from the printing plane when the key-lever is at the limit of its printing stroke, comprising a sub-lever to which said

- momentum acquiring means is connected and a sub-lever connected to said key-lever, said sub-levers having progressively rolling contact to transmit decreasing force on printing actuation of said key-lever. 5
25. In a typewriting machine, in combination, a type carrier, a key-lever, devices including a momentum acquiring means whereby on printing actuation of said key-lever, 10 said type carrier is moved to the printing plane, and thereafter assumes a position away from the printing plane when the key-lever is at the limit of its printing stroke, a bell crank lever to one arm of which said 15 momentum acquiring means is connected, and a sub-lever connected to said key-lever and disposed to actuate said bell crank lever by contacting the other arm of said bell crank lever progressively toward the ful- 20 crum of said bell crank lever. 20
26. In a typewriting machine, in combination, a type carrier, a key-lever, devices including a momentum acquiring means whereby on printing actuation of said key- 25 lever, said type carrier is moved to the printing plane, and thereafter assumes a position away from the printing plane when the key-lever is at the limit of its printing stroke, a bell crank lever to one arm of which said 30 momentum acquiring means is connected, and a sub-lever, fulcrumed independently of said bell crank lever, connected to said key-lever and disposed to actuate said bell crank lever by contacting the other arm 35 of said bell crank lever progressively toward the fulcrum of said bell crank lever. 35
27. In a typewriting machine, in combination, a type carrier, a key-lever, devices whereby on printing actuation of said key- 40 lever said type carrier is moved to the printing plane, comprising means adapted to relieve the type carrier from the direct im- 45 pulse of said key-lever prior to printing im- 50 pression, said means comprising a pair of levers respectively operatively connected to said type carrier and said key-lever, the levers of said pair comprising power trans- 55 mitting portions adapted to move toward and from each other, and a spring adapted 60 to move the lever of said pair which is connected to said type carrier in a direction to cause said portions of said two levers to engage. 65
28. In a typewriting machine, in combina- 55 tion, a type carrier, a key-lever, devices whereby on printing actuation of said key- lever said type carrier is moved to the printing plane, comprising means adapted to relieve the type carrier from the direct im- 60 pulse of said key-lever prior to printing im- 65 pression, said means comprising a pair of sub-levers respectively operatively connected to said type carrier and said key-lever, the levers of said pair comprising power trans- mitting portions adapted to move toward
- and from each other, and a spring adapted to move the lever of said pair which is connected to said type carrier in a direction opposed to its printing movement. 70
29. In a typewriting machine, in combina- 75 tion, a type carrier, a key-lever, and devices whereby on printing actuation of said key- lever said type carrier is moved to the printing plane, comprising means adapted to relieve the type carrier from the direct im- 80 pulse of said key-lever prior to printing im- 85 pression, said means comprising a sub-lever connected to said type carrier and a sub- lever connected to said key-lever, said sub- 90 levers coöperating to transmit increasing rate of movement to the first mentioned sub- 95 lever on printing actuation of said key- lever. 100
30. In a typewriting machine, in combina- 95 tion, a type carrier, a key-lever, and devices whereby on printing actuation of said key- lever said type carrier is moved to the printing plane, comprising means adapted to relieve the type carrier from the direct im- 105 pulse of said key-lever prior to printing im- 110 pression, said means comprising a sub-lever connected to said type carrier and a sub- lever connected to said key-lever, said sub- 115 levers coöperating to transmit increasing rate of movement to the first mentioned sub- 120 lever on printing actuation of said key-lever, one of said sub-levers being mounted to move out of contact with the other. 125
31. In a typewriting machine, in combina- 100 tion, a type carrier, a key-lever, and devices whereby on printing actuation of said key- lever said type carrier is moved to the printing plane, comprising a pair of toggles oper- 105 atively connected to each other, one of which is operatively connected to said carrier, a 110 pair of levers one of which is connected to one of said toggles and the other to said key- lever, the levers of said pair comprising power transmitting portions adapted to move toward and from each other, and to move from each other on printing actuation of said key-lever. 115
32. In a typewriting machine, in combina- 115 tion, a type carrier, a key-lever, devices whereby on printing actuation of said key- lever said type carrier is moved to the printing plane, comprising a pair of toggles oper- 120 atively connected to each other, one of which is operatively connected to said carrier, a 125 pair of levers one of which is connected to one of said toggles and the other to said key- lever, the levers of said pair comprising power transmitting portions adapted to move toward and from each other, and to move from each other on printing actuation of said key-lever, and a spring adapted to move said portion of said lever connected to said toggle toward said other portion. 130
33. In a typewriting machine, in combina- 130 tion, a type carrier, a key-lever, devices where-

by on printing actuation of said key-lever said type carrier is moved to the printing plane, comprising a pair of toggles operatively connected to each other, one of which is operatively connected to said carrier, a pair of levers one of which is connected to one of said toggles and the other to said key-lever, the levers of said pair comprising power transmitting portions adapted to 10 move toward and from each other, and to move from each other on printing actuation of said key-lever, and a weight operatively connected to one of said toggles so as to expend momentum to move one of said 15 power transmitting portions from the other power transmitting portion at a predetermined point in the path of movement of said carrier toward said printing plane.

34. In a typewriting machine, in combination, a type carrier, a key-lever, devices whereby on printing actuation of said key-lever said type carrier is moved to the printing plane, comprising means adapted to relieve the type carrier from the direct impulse of said key-lever prior to printing 20 impression, said means comprising a pair of sub-levers respectively operatively connected to said type carrier and said key-lever, the levers of said pair comprising 25 power transmitting portions adapted to move toward and from each other, and a momentum acquiring means connected to said first mentioned sub-lever adapted to force the type carrier to printing impression 30 while so relieved.

35. In a typewriting machine, in combination, a type carrier, a key-lever, devices whereby on printing actuation of said key-lever said type carrier is moved to the printing plane, comprising means adapted to relieve the type carrier from the direct impulse of said key-lever prior to printing 40 impression, said means comprising a pair of sub-levers respectively operatively connected to said type-carrier and said key-lever, the levers of said pair comprising power transmitting portions adapted to move into and out of engagement with each other, and a momentum acquiring means 45 connected to said first mentioned sub-lever adapted to force the type carrier to printing impression while so relieved.

36. In a typewriting machine, in combination, a type carrier, a key-lever, devices whereby on printing actuation of said key-lever said type carrier is moved to the printing plane, comprising means adapted to relieve the type carrier from the direct impulse of said key-lever prior to printing 55 impression, said means comprising a pair of sub-levers respectively operatively connected to said type carrier and said key-lever, the levers of said pair comprising power transmitting portions adapted to move toward and from each other, a spring adapted 60

to move the lever of said pair which is connected to said type carrier in a direction opposed to its printing movement, and a momentum acquiring means connected to said first mentioned sub-lever adapted to 70 force the type carrier to printing impression while so relieved.

37. In a typewriting machine, in combination, a type carrier, a key-lever, devices whereby on printing actuation of said key-lever said type carrier is moved to the printing plane, comprising means adapted to relieve the type carrier from the direct impulse of said key-lever prior to printing 75 impression, said means comprising a pair of sub-levers respectively operatively connected to said type carrier and said key-lever, the levers of said pair comprising power transmitting portions adapted to move toward and from each other, a spring 80 adapted to move the lever of said pair which is connected to said type carrier in a direction to cause said portions of said two sub-levers to engage, and a momentum acquiring means connected to said first mentioned 85 sub-lever adapted to force the type carrier to printing impression while so relieved.

38. In a typewriting machine, in combination, a type carrier, a key-lever, devices whereby on printing actuation of said key-lever said type carrier is moved to the printing plane, comprising means adapted to relieve the type carrier from the direct impulse of said key-lever prior to printing 90 impression, said means comprising a sub-lever connected to said type carrier and a sub-lever connected to said key-lever, said sub-levers coöperating to transmit increasing rate of movement to the first mentioned sub-lever on printing actuation of said key-lever, and a momentum acquiring means connected to said first mentioned sub-lever 95 adapted to force the type carrier to printing impression while so relieved.

39. In a typewriting machine, in combination, a type carrier, a key-lever, devices whereby on printing actuation of said key-lever said type carrier is moved to the printing plane, comprising means adapted to relieve the type carrier from the direct impulse of said key-lever prior to printing 100 impression, said means comprising a sub-lever connected to said type carrier and a sub-lever connected to said key-lever, said sub-levers coöperating to transmit increasing rate of movement to the first mentioned sub-lever on printing actuation of said key-lever, one of said sub-levers being mounted to move out of contact with the other, and a momentum acquiring means connected to 105 said first mentioned sub-lever adapted to force the type carrier to printing impression 110 while so relieved.

40. In a typewriting machine, in combination, a type carrier, a key-lever, an escape- 115

ment, devices whereby on printing actuation of said key-lever said type carrier is moved to the printing plane, comprising a lever operatively connected to said carrier, a lever 5 operatively connected to said key-lever, said two levers having portions adapted to move toward and from each other, and means adapted to arrest the printing actuation of said key-lever and thereby cause one of said 10 portions to move from the other and operate the escapement.

41. In a typewriting machine, in combination, a type carrier, a key-lever, an escapement, devices whereby on printing actuation of said key-lever said type carrier is moved to the printing plane, comprising a lever operatively connected to said carrier, a lever 15 operatively connected to said key-lever, said two levers having portions adapted to move toward and from each other, and a stop adapted to arrest the printing actuation of said key-lever and thereby cause one of said portions to move from the other and operate the escapement.

42. In a typewriting machine, in combination, a type carrier, a key-lever, an escapement, devices whereby on printing actuation of said key-lever said type carrier is moved to the printing plane, means adapted 20 to actuate said escapement after the key-lever is at the limit of its printing stroke, comprising a lever forming a part of said actuating means, and a universal bar movable longitudinally of one arm of said lever, said lever carrying a relatively movable element adapted to move said universal bar.

43. In a typewriting machine, in combination, a type carrier, a key-lever, an escapement, devices whereby on printing actuation of said key-lever said type carrier is moved to the printing plane, means adapted to actuate said escapement after the key-lever is at the limit of its printing stroke, comprising a lever forming a part of said actuating means, and a universal bar movable longitudinally of one arm of said lever, said lever carrying a swiveled element adapted to move said universal bar.

44. In a typewriting machine, in combination, a type carrier, a key-lever, an escapement, devices whereby on printing actuation of said key-lever said type carrier is moved to the printing plane, means adapted to actuate said escapement after the key-lever is at the limit of its printing stroke, comprising a lever forming a part of said actuating means, and a universal bar movable longitudinally of one arm of said lever, said lever carrying a relatively movable element adapted to move said universal bar, said movable element comprising a fork adapted to straddle said universal bar.

45. In a typewriting machine, in combination, a type carrier, a key-lever, devices including a momentum acquiring means

whereby on printing actuation of said key-lever, said type carrier is moved to the printing plane, and thereafter assumes a position away from the printing plane when the key-lever is at the limit of its printing 70 stroke, comprising a sub-lever to which said momentum acquiring means is connected and a sub-lever connected to said key-lever, said sub-levers coöperating to transmit varying force on printing actuation of said key-lever, and means adapted to arrest said key lever prior to printing impression by said type carrier.

46. In a typewriting machine, in combination, a type carrier, a key-lever, an escapement, devices including a momentum acquiring means whereby on printing actuation of said key-lever, said type carrier is moved to the printing plane, and thereafter assumes a position away from the printing 80 plane when the key-lever is at the limit of its printing stroke, comprising a sub-lever to which said momentum acquiring means is connected, a sub-lever connected to said key-lever, said sub-levers coöperating to transmit varying force on printing actuation of said key-lever, and means adapted to actuate said escapement when said key-lever is at the limit of its printing stroke.

47. In a typewriting machine, in combination, a type carrier, a key-lever, devices whereby on printing actuation of said key-lever, said type carrier is moved to the printing plane, and thereafter assumes a position away from the printing plane when 95 the key-lever is at the limit of its printing stroke, comprising a sub-lever to which said momentum acquiring means is connected, a sub-lever connected to said key-lever, said sub-levers coöperating to transmit increasing 100 rate of movement to the first mentioned sub-lever on printing actuation of said key-lever, and a momentum acquiring device comprising a weight operatively connected to said type carrier so as to initially move 110 toward the printing plane.

48. In a typewriting machine, in combination, a type carrier, a key-lever, a sub-lever operatively connected to said type carrier, a sub-lever operatively connected to 115 said key-lever, said sub-levers coöperating to transmit increasing rate of movement to the first mentioned sub-lever on printing actuation of said key-lever, a weight operatively connected to said first mentioned 120 sub-lever, and means whereby the printing actuation of said key-lever is arrested prior to printing impression, said sub-levers being adapted to operate so as to relieve the type carrier from the direct impulse of said 125 key-lever prior to printing impression.

49. In a typewriting machine, in combination, a type carrier, a key-lever, a sub-lever operatively connected to said type carrier, a sub-lever operatively connected to said 130

key-lever, said sub-levers coöperating to transmit increasing rate of movement to the first mentioned sub-lever on printing actuation of said key-lever, a weight operatively connected to said first mentioned sub-lever, and means whereby the printing actuation of said key-lever is arrested prior to printing impression, said sub-levers being adapted to operate so as to relieve the type carrier 10 from the direct impulse of said key-lever prior to printing impression and said weight being connected to force the type carrier to printing impression while so relieved.

50. In a typewriting machine, in combination, a type carrier, a key-lever, an escapement, a sub-lever operatively connected to said type carrier, a sub-lever operatively connected to said key-lever, said sub-levers coöperating to transmit increasing rate of movement to the first mentioned sub-lever on printing actuation of said key-lever, a weight operatively connected to said first mentioned sub-lever, means whereby the printing actuation of said key-lever is arrested prior to printing impression, said sub-levers being associated so as to relieve the type carrier from the direct impulse of said key-lever prior to printing impression and said weight being connected to force the type carrier to printing impression while so relieved, and means adapted to actuate said escapement after said key-lever is at the limit of its printing stroke.

51. In a typewriting machine, in combination, a plurality of radially disposed type actions, a member carried by each of said actions, a universal bar extending transversely across the machine and curved to have a uniform relative position beneath each member, a plurality of arms supporting said universal bar and insuring a substantially parallel movement of all parts thereof, a universal rock shaft, some of said first-mentioned arms being connected therewith, and means connected through said universal rock shaft for adjusting the relative position of the universal bar.

52. In a typewriting machine, in combination, a plurality of radially disposed type actions, a member carried by each of said actions, a universal bar extending transversely across the machine and curved to have a uniform relative position beneath each member, a plurality of arms supporting said universal bar and insuring a substantially parallel movement of all parts thereof, a universal rock shaft, some of said first-mentioned arms being connected therewith, an escapement mechanism, and intermediate 60 connections between the escapement mechanism and the universal bar.

53. In a typewriting machine, in combination, a plurality of radially disposed type actions, a member carried by each of said actions, a universal bar extending trans-

versely across the machine and curved to have a uniform relative position beneath each member, a plurality of arms supporting said universal bar and insuring a substantially parallel movement of all parts thereof, a universal rock shaft, some of said first-mentioned arms being connected therewith, an escapement mechanism, intermediate connections between the escapement mechanism and the universal bar, and a return spring associated with said intermediate connections.

54. In a typewriting machine, in combination, a plurality of radially disposed type actions, a member carried by each of said actions, a universal bar extending transversely across the machine and curved to have a uniform relative position beneath each member, a plurality of arms supporting said universal bar, a universal rock shaft, some of said first-mentioned arms being connected therewith, an escapement mechanism, intermediate connections between the escapement mechanism and the universal bar, and a return spring coiled about said connections and coacting against a relatively fixed part of the machine at one end thereof.

55. In a typewriting machine, in combination, a plurality of radially disposed type actions, a universal bar extending transversely across the machine and curved to have a uniform relative position with respect to each action, a plurality of arms supporting said universal bar and insuring a substantially parallel forward movement of all parts thereof, a universal rock shaft, some of said first-mentioned arms being connected therewith, a reverse escapement mechanism, intermediate connections between the escapement mechanism and the universal bar, a return spring coiled about said connection and coacting against a relatively fixed part of the machine at one end thereof, and means for adjusting the tension of said spring comprising a self-locking adjusting nut.

56. In a typewriting machine, in combination, a plurality of radially disposed type actions, a curved universal bar extending transversely across the machine and operatively associated with said type actions, a plurality of arms supporting said universal bar, a universal rock shaft, some of said first-mentioned arms being connected therewith, an escapement mechanism, intermediate connections between the escapement mechanism and the universal bar, a return spring coiled about said connection and coacting against a relatively fixed part of the machine at one end thereof, and means for regulating the timing of the escapement mechanism with respect to the movement of the universal rock shaft.

57. In a typewriting machine, in combi-

- nation, an escapement mechanism, a movable type carrier, energy-storing means other than said type carrier, an actuating key having a limited movement to effect a storage of energy in said means, and means to convert said stored energy into printing movement of said type carrier and actuation of said mechanism after arrest of movement of said key.
- 10 58. In a typewriting machine, in combination, an escapement mechanism, a movable type carrier, energy-storing means other than said type carrier, an actuating key having a limited depression, and operative connecting means between said elements to effect a storage of energy in said energy-storing means upon depression of said key and to convert such stored energy into printing movement of said type carrier and actuation of said mechanism after depression of said key to its limit, said connecting means including a lost motion device between said key and said type carrier and a second lost motion device between said type carrier and said escapement mechanism.
- 15 59. In a typewriting machine, in combination, a movable type carrier, an actuating key therefor, and operative connecting means between said elements including two sub-levers having rocking engagement with each other, one of said sub-levers having a pull connection with said key and the other having a thrust connection with said type carrier.
- 20 60. In a typewriting machine, in combination, a movable type carrier, an actuating key therefor, operative connecting means between said elements including two sub-levers having rocking engagement with each other and one having a pull connection with said key and the other having a thrust connection with said type carrier.
- 25 61. In a typewriting machine, in combination, a movable type carrier, an actuating key therefor, operative connecting means between said elements including two pivoted sub-levers having rocking engagement with each other, and means to adjust the axis of rotation of one of said sub-levers relative to the other.
- 30 62. In a typewriting machine, in combination, a movable type carrier, an actuating key therefor, operative connecting means between said elements comprising two pivoted sub-levers having rocking engagement with each other and one having a pull connection with said key and the other having a thrust connection with said type carrier, and means to adjust the axis of rotation of said sub-lever having a thrust connection relative to the other.
- 35 63. In a typewriting machine, in combination, a movable type carrier, an actuating key therefor, and operative connecting means between said elements comprising two fore and aft extending sub-levers having a rocking contact with each other and one having a pull connection with said key and the other having a thrust connection with said type carrier, the points of contact of said sub-levers during operation assuming a substantially horizontal travel toward the axis of said sub-lever having the thrust connection with said type carrier.
- 40 64. In a typewriting machine, in combination, a movable type carrier, an actuating key, and operative connecting means between said elements to insure movement of said type carrier to its printing limit with a gradual reduction of its momentum during the final portion of its travel, said means including two members having rocking engagement with each other during operation of said key.
- 45 61. In a typewriting machine, in combination, a movable type carrier, an actuating key therefor, operative connecting means between said elements including two pivoted sub-levers having rocking engagement with each other, and means to adjust the axis of rotation of one of said sub-levers relative to the other.

In testimony whereof I affix my signature, in the presence of two witnesses.

NILS H. ANDERSON.
